UNITED STATES PATENT OFFICE.

CHARLES E. SMITH, OF CLEVELAND, OHIO, ASSIGNOR TO THE ACME MACHINERY COMPANY, OF CLEVELAND, OHIO, A CORPORATION OF OHIO.

FLOATING PUNCH FOR NUT MACHINES.

Application filed April 28, 1923. Serial No. 635,263.

This invention relates to nut forming machines and more particularly, to the mounting or supports for the operating tools or punches thereof.

- 5 The object of the invention is to so mount the relatively movable telescoping inner and outer punch members as to enable them to automatically maintain proper alignment with each other or, in other words, be self-
 10 adjusting or accommodating to each other, to thereby avoid the otherwise harmful effects of misalignment of the parts and strains upon the tools which might injure the same.
 15 Further objects of the invention are in part obvious and in part will appear more in detail hereinafter.

In the drawings, Fig. 1 is a partial longitudinal sectional elevation through a nut making machine embodying the invention; Fig. 2 is a similar detail view through the crowning and piercing tools and the mounting therefor; and Fig. 3 is a detail cross section on the line 3—3, Fig. 2.

- 20 The invention may be applied to any form of nut making machine or indeed any machine involving relatively movable telescoping inner and outer punch members, but for convenience of illustration has been shown applied to a nut machine of the type illustrated in the patent for nut machine, No. 1,346,889, granted July 20, 1920, to E. Hollings. Said machine comprises a suitable frame 1 supporting the usual die block 2 and operating shafts 3, 4, driven in any suitable manner and inter-connected in timed relation by the gearing represented conventionally at 5. As is usual, the nut blanks are cut off in succession from a bar fed step by step to the machine, being first partially separated by the indenters 6 actuated by suitable cams 7 on shaft 4, each succeeding nut blank being carried into the die block by a tubular cut off tool 8 opposed to which is a tubular crowning tool 9. When the blank, illustrated at 10 is carried into the die block it is pierced by an inner piercing punch 11 opposed to which is the slug thinner and ejecting punch 12. The blank is also compressed between the cut off tool 8 and crowner 9 and by the crowner is carried out of the die block and after ejection of the slug is delivered as a finished pressed nut blank.

- 55 The several operating tools and particu-

larly the inner punches 11, 12 and outer or tubular punches 8, 9 are arranged in pairs opposed to each other on opposite sides of the blank, each pair comprising telescopically related and aligned inner and outer punch members. The drawings show the punch members 9 and 11 as actuated by suitable cam devices on shaft 3, as in said prior patent, and similar suitable devices, not shown, are provided at the other end of the machine for actuating the similarly arranged inner and outer punch members 12, 8.

In such machines some difficulty has been experienced with breakage of and injury to the punches due to lack of proper alignment of the telescopically related tools, either due to inaccurate workmanship or adjustment or to wear or use of the machine bringing about a condition of lack of alignment.

The present invention overcomes such objections by a special mounting of the punch tools. As illustrated particularly in Figs. 2 and 3 the outer or crowning punch 9 is of the usual tubular form with one portion thereof threaded, as at 13, to enter a split or two part clamping member 14, 14^a clamped between a cap 15 and the body portion of a slide 16 which extends rearwardly to and is actuated by a suitable cam or cams on the shaft 3, as in said prior patent. Cap 15 is held to the slide 16 in any suitable manner, as by the bolts and nuts 17. This tubular outer punch member or crowning tool is therefore readily held in its movable carrying slide but is adjustable longitudinally thereof to determine the final blank thickness and for proper cooperation with the tools at the other end of the machine by loosening up the clamping parts and screwing the punch forwardly or rearwardly, as will be readily understood. The rear end of said punch may be closed by a sleeve guide 18 and the parts may also be provided with ports and passages 19 for circulating cooling liquid thereto if desirable.

The inner or piercing punch 11 is telescopically related to the crowning punch 9 and slides longitudinally within the same. It is guided in an opening at the working end of the crowning tool and in a similar opening in the sleeve 18 and has a rearward extension provided with a collar-like head 20 for adjustment to its operating slide 21 which reciprocates in the slide 16 and is also

actuated by suitable cams on shaft 3. The securing means for the punch 11 comprises a pair of upper and lower threaded clamping blocks 22, 22^a provided with vertically extending side ribs 23 entering similarly shaped guiding ways in the slide 21 and clamped between a portion of the slide and a cap 24 held thereto by nuts 25 on the bolts 26. These clamping members hold between them a hollow sleeve 27 and a slot threaded block 28. The latter is at the rear end of the inner punch and forms an abutment to receive the throws of the punch head 20, the outer diameter of which is slightly smaller than the inner diameter of the threads in the clamping blocks. The threaded sleeve 27 is held in said clamping blocks surrounding the punch shank and in advance of its head. This sleeve has an opening therein through which the punch shank extends, said opening being slightly larger than the punch shank, say several thirty seconds of an inch. It is adjusted in the clamping blocks to a position in which a slight clearance, of say several thirty seconds of an inch, and indicated at 30, is left between the head of the punch and said sleeve.

The punch as a whole may be adjusted longitudinally in the machine in the same manner as the crowning tool 9, to wit, by loosening up the clamping blocks and by a screwing operation adjusting the block 28 and sleeve 27 forwardly or rearwardly to the desired point, but in the final position of adjustment the clearance 30 is left as before described.

As a consequence the punch 11 is secured to its operating slide but has a floating connection therewith, being permitted a slight longitudinal motion with respect to said slide determined by the clearance 30 and also a slight lateral or transverse motion with respect to said slide, determined by the clearance between the outer surface of the punch shank and the inner surface of sleeve 27.

With this arrangement extreme accuracy in workmanship is not essential as the punch can be inserted in telescoping or sliding relation with the crowning tool and the block 28 and sleeve 27 adjusted and clamped as stated, and the rear end of the punch may be allowed to go and come as it pleases, always adjusting or accommodating itself to either inaccuracies of workmanship or any possible mis-alignment due to wear and tear upon the parts of the machine or to adjustment thereof or to attempted change of position or lack of alignment due to effect upon the tools by the volume or thickness thereof.

Without further description it is of course, obvious that the punches 8 and 12 at the other end of the machine may be mounted and supported in the same manner as those described, so that the inner punch 8 will have a floating connection to its operating slide and automatically adjust or accommodate itself to conditions of mis-alignment.

What I claim is:—

A nut machine, comprising a frame provided with a die block having a blank receiving opening, a carrier guided on said frame and carrying a hollow punch arranged to enter said opening, a second punch having a shank slideable with a bearing fit within said hollow punch and at its outer end being provided with a head, and a movable slide for operating said second punch, said slide being provided with a cavity to receive the head end of said second punch, said cavity being enlarged laterally and longitudinally beyond the diameter of said shank and length of said head to permit lateral and longitudinally lost motion between the slide and second punch, to thereby enable said second punch to maintain its bearing fit in the hollow punch regardless of alignment of said slide with the die block opening.

In testimony whereof I hereby affix my signature.

CHARLES E. SMITH.
